Patented June 10, 1975

235,352

PHONOGRAPH STYLUS

Robert L. Deschamps, Wheaton, Ill., assignor to Shure
Brothers Incorporated, Evanston, Ill.

Filed Dec. 12, 1973, Ser. No. 424,186

Term of patent 14 years

Int. Cl. D14—01; D14—99
U.S. Cl. D26—14 D

FIG.1

FIG.2

FIG.3

FIG.4

FIG.5

FIG.6

FIG.7

FIG. 1 is a top perspective view of a phonograph stylus showing my new design;

FIG. 2 is a bottom perspective view of the phonograph stylus;

FIG. 3 is one side view thereof, the other side being substantially identical;

FIG. 4 is a front view thereof;

FIG. 5 is a top plan view thereof;

FIG. 6 is a rear view thereof; and

FIG. 7 is a bottom plan view thereof.

I claim:

The ornamental design for a phonograph stylus, as shown and described.
